Atteys.

UNITED STATES PATENT OFFICE.

HERBERT H. HULL, OF LAKEWOOD, OHIO, ASSIGNOR, BY MESNE ASSIGNMENTS, TO
ANCHOR CAP & CLOSURE CORPORATION, OF BROOKLYN, NEW YORK, A CORPO-
RATION OF NEW YORK.

SIDE-SEAL CLOSURE.

1,253,492.

Specification of Letters Patent. Patented Jan. 15, 1913.

Application filed March 16, 1917. Serial No. 155,217.

To all whom it may concern:

Be it known that I, HERBERT H. HULL, a citizen of the United States, and a resident of the city of Lakewood, in the county of 5 Cuyahoga, State of Ohio, have invented certain new and useful Improvements in Side-Seal Closures, of which the following is a specification.

This invention relates broadly to closures 10 and more specifically to a side seal.

The principal object of the present invention is to provide a side seal of a character wherein the sealing operation brings into play forces acting angularly to the 15 wall of the container whereby a compressible gasket is forcibly seated against the side of the container.

Another object of the present invention is to provide a side seal wherein there is a 20 minimum distortion of metal in order to obviate the destruction of lacquer on the caps.

A still further object of the present invention is to provide a cap which when sealed against a closure presents a bead 25 wherein the excess of metal in the sealing operation is flowed outwardly toward the edge of the bead, and wherein substantially a smooth annular rim is presented above the sealing bead.

30 A still further object of the present invention is to provide a cap adapted to be sealed to form a side seal, and wherein the excess metal in sealing is taken care of without formation of grooves in the finished seal.

Other and further objects of the present invention will in part be obvious and will 35 in part be pointed out hereinafter in the specification following by reference to the 40 accompanying drawings in which like parts are represented by like characters throughout the several figures thereof.

Figure 1 is a sectional detail view illustrating the cap in accordance with this invention prior to the sealing operation.

Fig. 2 is a detail view showing the relation of parts immediately after the seal is completed and illustrating the action of the sealing chucks.

50 Fig. 3 is a view illustrating a complete sealed package.

Heretofore in the art of side seals it has been customary to provide a groove to take up the excess metal formed during the sealing operation. Such grooves to a more or 55 less extent tend to break the lacquer skin

and to such an extent are somewhat undesirable. Furthermore, caps of the type using a groove usually include slightly more metal in their manufacture than is necessary in the invention hereinafter to be more 60 fully described.

The present invention comprises a side seal cap wherein the cap is formed in such manner as to be adapted to be sealed and 65 permit the excess metal, due to the sealing operation, to be taken up in the bead of the cap in the outwardly extending portion thereof rather than by formation of grooves. Also in the type of closure comprising this 70 invention the sealing action takes place under angular forces so that the gasket is subjected to what might be termed a toggle action, which very tightly compresses the gasket against the side wall of the container. 75

Referring now more particularly to the drawings, it will be noted that the cap comprises a cover portion 1 which preferably includes a downwardly depending flange 2, an outwardly extending wall 4 which may 80 be slightly depressed, as illustrated at 5 in Fig. 1. This outwardly extending wall is continued in the form of an angularly disposed skirt 6 which is of slightly less diameter at the bottom than at the top. This 85 diameter enables the cap to securely and conveniently carry a suitable gasket member 7 which before the seal is completed passes freely over the side wall of the container 8 which is preferably a glass receptacle of the tumbler type and may be formed with a cylindrical portion 9 adjacent the mouth thereof.

In the sealing operation the bead is compressed between an upper chuck 10 and a 95 lower chuck 11 in such manner as to straighten the outwardly extending wall 4 and to incline the skirt 6 to an inclination of preferably about twenty-five (25) degrees relatively to the cylindrical side wall 9. 100 Under this action it is to be noted that the gasket 7 is compressed between the outwardly extending wall 4 and the skirt 6 somewhat after the action of a toggle member. This forces the gasket 7 very tightly 105 against the cylindrical side wall 9, and the excess metal of the sealing operation is disposed of by being flowed into the rib or edge 12 of the finished closure.

Having thus described my invention 110 what I claim is:—

1. In a closure, a cover portion, a depend-

- ing rim adjacent said cover portion, a ring extending at substantially right angles to said rim, a substantially straight-walled skirt angularly disposed to extend inwardly 5 relatively to said ring, a gasket between said ring and skirt and adapted to be tightly compressed against the side wall of a substantially incompressible container by 10 increasing the angularity of said skirt relatively to said ring, substantially as specified.
2. In a sealed package, in combination, a substantially incompressible container, a cover cap extending over the mouth of said container, said cover cap comprising an outwardly extending substantially flat ring, an 15 inwardly inclined skirt forming the frustum of a cone integral with said ring, and a compressible gasket between said ring and said skirt and under compression against 20 the side wall of said container whereby the cross-section of said ring, said gasket and

said skirt is substantially a right angle triangle.

3. As an article of manufacture, a sealed package comprising a container having substantially straight cylindrical side wall adjacent the mouth thereof, a cover cap portion extending over the mouth of said container, and a skirt extending below the cover portion and over the straight smooth cylindrical side wall and comprising the frustum of a cone and angularly disposed relatively to said straight cylindrical side wall of the said container and spaced apart therefrom, the portion adjacent to and above said frustum of a cone extending substantially at right angles to the side wall of the container, and a suitable gasket under compression between said skirt and said smooth side wall.

HERBERT H. HULL.
